(57) **CLAIM**

The ornamental design for a notebook computer, as shown and described.

DESCRIPTION

FIG. 1 is a perspective view of a notebook computer showing our new design in a standing state;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof in an opened state;

FIG. 9 is a perspective view thereof in a flattened state; and, FIG. 10 is an enlarged view of the indicated portion of FIG. 9.

The dashed broken lines illustrate portions of the notebook computer and form no part of the claimed design.

1 Claim, 10 Drawing Sheets
